DUCT COUPLING

Ake Ahlrot, Amiralsgatan 10,
S-552 48 Jonkoping, Sweden

Continuation-in-part of design application Ser. No.
279,067, Aug. 9, 1972. This application Nov. 17,
1972, Ser. No. 307,365

Claims priority, application Sweden Feb. 11, 1972

Term of patent 14 years

Int. Cl. D23—01
U.S. Cl. D23—43

Fig. 1

Fig. 2

Fig. 3

FIG. 1 is a plan view of a duct coupling embodying my new design;

FIG. 2 is a side elevation of the element shown in FIG. 1 with a portion broken away to show the element in longitudinal cross-section; and

FIG. 3 is an end view of the element with a lower portion in transverse cross-section as indicated by the irregular section line 3—3 of FIG. 2.

This is a continuation-in-part of design application Ser. No. 279,067, filed Aug. 9, 1972, now abandoned.

I claim:

The ornamental design for a duct coupling, substantially as shown.
